ENVELOPE FEEDER

Jacob R. Lauffer, Valley Stream, N. Y., assignor
to Miller-Lauffer Printing Equipment Corp.,
New York, N. Y., a corporation of New York

Application August 15, 1947, Serial No. 768,744

6 Claims. (Cl. 271—2)

1

This invention relates to printing presses, and more particularly to presses designed to print impressions with great index accuracy on previously separated pieces of paper, such for example as envelopes, which are fed in succession to and past printing position. Specifically the invention is concerned with certain feeding and handling mechanisms by means of which individual pre-folded envelopes are successively removed at a transfer position from a solid or face-to-face stack of such envelopes, and are then advanced one after the other towards a place or station where they are to be individually acted upon or processed as, for example, printed or the like. While the feeding and handling mechanisms according to the present invention appear to be chiefly useful when embodied in and forming part of a high-speed printing press (and accordingly are here described for purposes of illustration within that specific frame of reference), I want to make clear my purpose, intention and understanding that the said mechanisms may also be used in the feeding and handling of prefolded envelopes otherwise than to a printing operation, and that my invention is therefore not limited to use thereof for the specific purpose of printing but comprehends as well use for other purposes and operations which, so far as my particular invention is concerned, may be regarded as equivalent or analogous to printing.

The present invention was developed with particular reference to the printing of impressions in the extreme corners of envelopes. It is believed, however, that the invention is useful in connection with the printing of impressions on any kind of previously separated sheets of paper, where the dual requirements of high speed and an accurate index are present.

The fastest presses now commercially available for the printing of impressions in the corners of envelopes utilize a rotary platen and type cylinder in conjunction with reciprocating mechanism for feeding envelopes from a supply to the printing position, and reciprocating mechanism for receiving envelopes from the printing position and delivering them to the finished stack. Such presses, as now commercially available, are rated at a standard capacity of 10,000 envelopes per hour, and have on occasion (without material loss of index accuracy) been operated at speeds of 15,000 envelopes per hour. At higher speeds than this, difficulties begin to appear, such as inaccuracy of indexing, jamming of the feed and delivery mechanism, and the like, which place an effective upper limit on the speed of such presses at approximately 15,000 envelopes per hour.

2

Other presses, in which the type reciprocates, have been used for printing impressions in the corners of envelopes, but while these are capable of accurate indexing they do not approach in speed the particular commercial presses just mentioned.

A press made in accordance with the present invention has printed impressions in the extreme corner of envelopes, with a high degree of index 10 accuracy, at a speed of 100,000 envelopes per hour. It possesses the advantages, additional to that of increased speed, that the impression can be applied in a position closer to the margin of the envelope than in the prior commercial presses 15 mentioned, and by way of contrast with reciprocating and rotary presses previously used for envelope printing, is comparatively simple to manufacture and can be maintained and operated by unskilled labor.

20 In this application I describe, as illustrative of my invention, one form of press capable of the high speeds and index accuracy mentioned above. Referring to the drawings annexed to and forming part of this application:

25 Fig. 1 is a side view looking at the side showing the motor drive, the operator normally working on the other side of the machine;

Fig. 2 is a top view;

Figs. 3, 4, 5 and 6 are longitudinal vertical sections taken from the lines 3—3, 4—4, 5—5, and 6—6 respectively, in Fig. 2;

Fig. 7 is a perspective view showing the type and platen cylinders and a portion of the envelope feeding system;

35 Fig. 8 shows a modification of elements of the envelope feeding system;

Fig. 9 is a perspective showing one of these elements of Fig. 8; and

Fig. 10 is an end view of a portion of the machine taken from line 10—10 in Fig. 1.

This machine comprises a horizontal frame 1 positioned at a convenient height above the floor, by legs 2. A comparatively small, vertical frame 3 is carried by the frame 1 and journals a rotary type cylinder 4 and platen cylinder 5 in cooperating relation.

In the drawings the left-hand end of the machine is the feeding end, the envelopes going continuously through the machine and being received 45 at its right-hand end.

A sub-frame 6 is supported between the adjacent legs 2 at the feeding end of the machine and somewhat below the level of the frame 1. This sub-frame 6 carries the feeding magazine 50 for the stack of envelopes.

This envelope feeding magazine includes a sub-

stantially horizontal endless conveyer belt 7 looped over horizontally spaced rollers 8 and working forwardly toward the machine between side guides 9. A horizontal stack of envelopes, with the envelopes substantially vertical and their faces juxtaposed, is laid on this belt 7 between the guides 9, with their flaps forwardly and pointing downwardly. The belt 7 frictionally engages the envelopes' bottom edges, the belt being preferably rubberized or the like to promote frictional engagement, and continuously urges the envelopes toward the machine. A forwardly and upwardly slanting abutment 10 is positioned at the machine end of the magazine, this abutment slanting in the form of ascending steps, and the envelopes are pushed against this abutment and through its action tilted forwardly.

A small, upwardly pointing pipe 12 directly in front of the abutment 10 ejects fluid such as compressed air against each foremost envelope below its flap to blow the latter outwardly a little. An air jet is most convenient. Care should be taken to keep the force down to a degree which does not blow the envelope's flap straight upwardly, while still being sufficient to free it from the envelope proper should it tend to stick due to its having been pressed thereagainst by the weight of the envelope stack.

The frame 1 journals horizontal axles 13 on either side of the type and platen cylinders 4 and 5, and laterally spaced sprocket wheels 14 are fixed to these axles in straddling alignment with the working pass of the type and platen cylinders. The sub-frame 6 journals an axle 15 to which laterally spaced sprocket wheels 16 are fixed, the spacing of these sprocket wheels 16 being slightly wider than that of the sprocket wheels 14. Laterally spaced conveyer loop 17 are looped over the sprocket wheels 14 and 16, and are in the form of sprocket chains to provide sprocket holes meshing with the various sprockets. Due to the sprocket wheel arrangement the chain loops 17 define straight horizontal sections straddling the type and platen cylinders 4 and 5 just outside of their working pass. It also provides straight ascending sections between the sprocket wheels 14 and 16, and these ascending sections go upwardly directly in front of the envelope feeding magazine. The chains 17 are tautly maintained by the sub-frame 6 journaling free-swinging levers 18 mounting sprocket wheels 19 resting on the bottom section of the loops of the sprocket chains 17. The combined weight of the lever 18 and sprocket wheels 19 is relied upon for this purpose, although additional weight or springs can be used to provide more force. The sprocket wheels 19 are fixed to an axle 20 to maintain the alignment of the assembly, this axle 20 being journaled by the levers 18.

The sprocket chain loops 17 must travel in mutual synchronization since all the sprockets are fixed to their various axles. These chains carry a series of spaced fingers 21 positioned in sets of laterally aligned fingers. In one form these fingers extend laterally upwardly and then inwardly from the chains and then project forwardly parallel to the chains. The fingers are formed from flat strip metal of relatively thin gauge. The pointing direction of the fingers is in the working direction of the chains. As the fingers ride around the sprocket wheels 16 and start upwardly, each set engages beneath the flap of the foremost envelope in the envelope feeding magazine and thus successively pick up the en-

velopes and carry them along between the type and platen cylinders 4 and 5. Due to the thin and flat character of these fingers they do not interfere appreciably with printing in the upper left hand corners.

When it is desired to print even closer to the upper left hand corners than is possible with the previously described fingers, the form shown by Figs. 8 and 9 may be used. In this instance the chains 17 have upstanding flat-faced plates 22 riveted to their individual links, at the appropriate spacings, and very small diametered pins 23 project inwardly from these flat-faced upstanding plates 22. Incidentally, the plates 22 are upstanding because the chains 17 actually straddle the platen cylinder 5 slightly below its upper level, the previously described fingers 21 also extending slightly upwardly before turning inwardly, as described. This relation of the chains with the cylinder 5 is because the fingers drag the envelopes by their flaps over flat guides 23 leading from the front end of the feeding magazine upwardly and around, to extend horizontally to the feeding nip of the cylinders 4 and 5, and horizontally from the discharging nip on the other side. These guides hold the envelopes parallel to the chains as the fingers drag them along.

Continuing, the chains are spread slightly apart from their ultimate relation, due to the spacing of the sprocket wheels 16, at the time the fingers first engage the envelope flaps. This provides some lateral leeway and makes the pick-up easier. As the chains travel upwardly they converge and therefore cause the fingers to move together. In the case of the secondly described fingers the abutment 22 at this time functions to center the envelopes, the abutments engaging their edges and the small diametered pins 23 permitting the envelopes to slide easily while being centered. The upstanding parts of the fingers 21 perform the same function.

To be more specific about the diameter of the pins 23, they should have a diameter about the same as or not substantially greater than the radius of the concave inner surface of the fold where the envelope flap joins the remainder of the envelope in the case of the ordinary paper envelope. The pins 23 should be as small as is consistent with their not bending or breaking when performing their function. In each instance the envelopes are fed between the type and platen cylinders in proper alignment therewith, but the fingers shown by Figs. 8 and 9 perform this function even more accurately and permit closer printing to the upper envelope corners. In fact for all practical purposes they do not interfere with the printing at all, because it is never desirable to print on the actual junctions of the flaps and envelopes proper.

The cylinders 4 and 5 are carried by axles 24 through which they are journaled by the frame 3, and on one side these axles extend to provide space between the cylinder ends and that side 65 of the frame 3. These axle extensions are fixed to intermeshing pinions 25 having pitch diameters equalling the working diameters of the cylinders 4 and 5, while the diameters of the latter are proportioned so that diameters of their type and platen surfaces are exactly equal. Therefore, the two cylinders must rotate in perfect synchronism without any adjustment. The sprocket wheels 14 on the right-hand side of the machine, on the discharge side of the cylinder, 75 have pitch diameters exactly equalling those of

the pinions 25 and the working diameters of the cylinders 4 and 5, and the axle 13 of these sprocket wheels and the axle 24 of the platen 5 have sprocket wheels 26 fixed to them which also have pitch diameters equalling those of the pinions 25 and, those of the sprocket wheels 14 just mentioned. A sprocket chain 27 is tautly looped around the sprocket wheels 26.

The type cylinder 4 mounts the type in the form of type plates 28 fastened to the periphery of the cylinder, the latter thus providing type mounts. One or more of these type plates may be provided, the machine being described having four spaced 90 degrees apart about its diameter. Each set of envelope flap-engaging fingers is spaced the same distance from the next set as the spacing of these type plates. In other words, as these fingers go around the right-hand sprocket wheels 14 they are also spaced 90 degrees apart relative those sprockets.

With the foregoing in mind it now becomes apparent that as the machine operates the equal diametered type and platen cylinders 4 and 5 must rotate in perfect synchronism with the envelopes carried along precision indexed with the type plates 28, regardless of how the machine is maintained. The synchronization is automatic and cannot be tampered with. Preferably the left-hand sprockets 14 have equal diameters with the other so that should they be inadvertently exchanged the synchronization of the machine is not affected. Interchange of the pinions 25 has no effect on the synchronization. No matter how mechanically inexperienced the operator, it is practically impossible to get the machine out of synchronization. High operating speeds cannot affect the synchronization.

The machine is powered by an electric motor 30 driving a pulley 31 through a gear box 32, with this pulley driving a belt 33 looped over a pulley 34 fixed to either the axle 13 to which the right-hand sprocket wheels 14 are fixed or to the axle 24 of the platen cylinder, the latter being preferable if the type and platen cylinders are hard to turn. Therefore, the chain loop sections powering the lower axle 24 of the platen cylinder 5, and the chain sections dragging the envelopes through the printing phase are all in tension. Since the sprocket chains all may be made exactly alike, and since the pitch diameters of the sprocket wheels are all the same, the wear is uniform in all instances. All this contributes to the machine operating as a precision printing press regardless of its operating speed and regardless of its maintenance. Only the pinions 25 need approach precision, but even in this instance the precision need not be high, since the pinions drive continuously without direction reversal. Even when they become worn the loss of synchronism is very slight and is entirely uniform.

In the case of a machine, constructed in accordance with this invention with the speed providing about from 50 R. P. M. to 410 R. P. M. and the type cylinder 4 carrying four type plates with the fingers appropriately spaced, the output is from 1200 to 100,000 envelopes per hour. The precision obtained is very high, so the printed envelopes are attractive in appearance.

As the printing speed of the press may be quite high, the centrifugal force applied to the envelopes as they go around the left hand sprocket wheels 14, may approach a degree involving the danger that the envelopes might become disengaged from the fingers. This danger is elimi-

nated by a plurality of friction drags 35 in the form of thin-gauge metal strips mounted by suitable arms so they function as cantilever springs pointing in the traveling direction of the envelope-conveying sprocket chains and declining theretowards. The first of this series of drags is quite close to the feeding end of the envelope feeding magazine, and it functions to settle the envelopes down on the fingers firmly, and the remainder contribute to this function. This series of drags goes around the sprocket wheels at the feeding end of the machine, thus pressing the envelopes down and preventing any trouble due to their disengaging from the fingers. The guides 23 extend throughout this distance and the friction drags 35 are positioned opposite them to lightly frictionally nip the envelopes between the drags and the guides.

As described so far the machine has printed the envelopes and is carrying them from the type and platen cylinders with the envelope flaps still engaged by the fingers. At this time it becomes necessary to disengage the envelope flaps from the fingers and remove the envelopes from the conveyer loops 17, so the envelopes can continue to the discharge end of the machine. This is done as follows:

The frame 1 journals two axles 36 with one beyond the right-hand axle 13 and the other one between this axle and the type and platen cylinders. Rollers 37 are fixed to these axles 36 with their peripheries slightly above the traveling level of the envelope-conveying chains and their fingers engaging the envelope flaps. These rollers 37 carry endless conveyer belts 38, and the left-hand axle 36 is connected with the right-hand axle 36, the left-hand axle 36 being powered by sprocket wheels 39 and a sprocket chain 40. These sprocket wheels and chain are designed to provide a gear ratio greater than unity to drive the belts 38. By making the rollers 37 with larger diameters than the sprocket wheels 14, it is also possible to provide, in effect, gearing having a ratio greater than unity.

In any event, the need is to drive these belts 38 at slightly higher velocities than the traveling speed of the conveyer chains 17. The rollers 37 should be close enough together to space the conveyer belts 38 so they properly support the envelopes.

With the above arrangement, as the envelopes leave the type and platen cylinders their leading edges ride up over the upwardly curving conveyer belt sections of the belts 38 and, since these are traveling at higher velocities, the envelopes are accelerated so their flaps free themselves from the flap-engaging fingers. Re-engagement is impossible because the envelopes are subsequently moving at faster speeds than the flap-engaging fingers, the latter finally diving downwardly over the right-hand sprocket wheels 14, while the envelopes continue to travel forwardly in a horizontal plane.

A plurality of rollers 41 are journaled above the belts 38 in a vertically moving manner so that they rest on the belt by reason of their weight. This weight adds to the weight of the envelopes to assure them being frictionally carried by the belts 38. These belts 38 may have surfaces that are rubberized or the like to enhance their frictional engagement with the envelopes and with rollers 41 they form a pinch into which the envelopes enter as shown in Fig. 5.

At high press operating speeds the envelopes may be shot from the ends of the belts 38 as they

loop downwardly around their right-hand rollers 37, and the printing press has a declining guide bar 42 for guiding such flying envelopes downwardly.

At the above place, where the envelopes leave the belts 38, the press has an envelope receiving magazine, the bottom of which is formed by conveyer belts 43 looped at one end over the right-hand axle 36, handily providing a gear drive for the belts 43 which is substantially less than unity so the belts 43 travel backwardly rather slowly. The guide bar 42 has an end that goes clear down and rests or is spring urged against the envelopes carried by the tops of the belts 43, whereby the belts 43 carry the printed envelopes backwardly one at a time and lying horizontally, the lower end of the guide 42 tending to permit the envelopes to pass only one at a time. The other ends of the belts 43 loop over an axle 44 journaled at the rearmost end of the machine, and to assure a positive drive the end of this axle 44 has a pulley 45 powered by an appropriately sized pulley 46 on the powered one of the shafts 13, with these two pulleys interconnected by a driving belt 47. A flat table 48 is positioned between the oppositely traveling sides of the conveyer belts 43, and lower end of the guide bar 42, when there are no envelopes beneath it bearing against this table top. The envelopes are carried over this table top on the traveling conveyers 43 until they reach upwardly inclining abutments 49 where they are wedged upwardly so the envelopes arrange themselves as a horizontal stack in the envelope receiving magazine.

The printing speed of the described printing press is at present limited largely by the dexterity of the operators in placing the envelope stacks in the feeding magazine and removing them from the storing magazine. It may prove expedient to provide automatic devices at these locations, particularly when extremely high printing speeds are desired. As the machine has been disclosed herein it prints at an extremely high rate of speed, as previously indicated. Its general shape is of advantage, it being not much wider than the envelopes and not too long in length. Its mode of operation is an advantage in that an operator can stand at one end and feed the envelopes to the feeding magazine, the envelopes then going through the machine without hesitancy, direction reversals, or the like, until they are eventually discharged at the other end of the machine into the receiving magazine where the operator can remove the stack of printed envelopes.

The machine is entirely driven through the powered, right-hand one of the axles 13. Through engagement of chains 17 with sprocket wheels 16 secured on shaft 15 (as shown in Figs. 1 and 3) power is transmitted to drive feed belt 7 which is looped about shaft 15, and the belt and these chains are therefore driven in timed relation with each other. Through engagement of chains 40 with sprocket wheel 39 on shaft 36 (as shown in Figs. 1 and 2) power is transmitted to drive the speed-up belts 38 at a suitably increased speed of travel over that of chains 17, by reason of the gearing greater than unity as described. All of the flexible elements requiring it are synchronized through tensioned spans, as previously noted. It is impossible for anything to get out of synchronization regardless of the machine operating speed.

It is to be understood that otherwise than as specifically described herein, the printing press is provided with the usual appurtenances. For example, it has inking rollers, generally indicated

at 50. Also, the various axles are journaled by proper bearings provided with proper arrangements for lubrication. It is possible to substitute flat steel belts having sprocket holes for the various sprocket chains. It has already been suggested that automatic devices be provided for loading and unloading the envelope magazines.

I claim:

1. An envelope feeder comprising two endless chains working in unison along substantially parallel paths a predetermined distance apart, rotatable sprockets for said chains mounted to cause said chains during one portion of their paths of travel simultaneously to ascend in straight lines in a generally upward direction, a plurality of pairs of lugs secured to said chains at uniformly spaced intervals along the same, one lug in each pair being secured to one of said chains in opposed relation to the other lug of said pair, each lug having a projecting portion shaped to penetrate beneath the folded flap of an envelope and to engage the concave surface of the fold at each end of said flap, the said portions projecting towards each other and remaining in alinement as the chains move, an envelope feed magazine including a powered feed belt having a substantially horizontal portion forming in part at least the floor of said magazine and a guide plate forming a side of said magazine, said substantially horizontal portion of the belt being adapted to support a stack of envelopes standing on edge with their flap-folds uppermost, their flaps folded down adjacent their respective bodies and their ends guided by said plate, and to propel them in the direction in which their flaps extend, said feed magazine being mounted to deliver envelopes successively to a position between the chains where the concave surfaces of the fold at each end of their flaps are simultaneously presented in the paths of travel of said lug projections for upward extraction of envelopes from the magazine as the lugs move upwardly along the substantially straight line portion of the chain paths, means to open the envelope flaps as they reach said position, and means to drive the powered feed belt in relation to the speed of the chains such that successive envelopes in the stack are delivered to successive pairs of lugs as the chains move.
2. An envelope feeder comprising two endless chains working in unison along substantially parallel paths a predetermined distance apart, rotatable sprockets for said chains mounted to cause said chains during one portion of their paths of travel simultaneously to ascend in straight lines in a generally upward direction, a plurality of pairs of cylindrical pins of diameter approximately equal to the inside diameter of an envelope flap-fold secured to said chains at uniformly spaced intervals along the same, one pin in each pair being secured to one of said chains in opposed relation to the other pin of said pair, said pins projecting towards each other and remaining in alinement as the chains move, an envelope feed magazine including a powered feed belt having a substantially horizontal portion forming in part at least the floor of said magazine and a guide plate forming a side of said magazine, said substantially horizontal portion of the belt being adapted to support a stack of envelopes standing on edge with their flap-folds uppermost, their flaps folded down adjacent their respective bodies and their ends guided by said plate, and to propel them in the direction

in which their flaps extend, said feed magazine being mounted to deliver envelopes successively to a position between the chains where the concave surfaces of the fold at each end of their flaps are simultaneously presented in the paths of travel of said pins for upward extraction of envelopes from the magazine as the pins move upwardly along the substantially straight line portion of the chains paths, means to open the envelope flaps as they reach said position, and means to drive the powered feed belt in relation to the speed of the chains such that successive envelopes in the stack are delivered to successive pairs of pins as the chains move.

3. An envelope feeder comprising two endless chains working in unison along substantially parallel paths a predetermined distance apart, rotatable sprockets for said chains mounted to cause said chains during one portion of their paths of travel simultaneously to ascend in straight lines in a generally upward direction, a plurality of pairs of lugs secured to said chains at uniformly spaced intervals along the same, one lug in each pair being secured to one of said chains in opposed relation to the other lug of said pair, each lug comprising a shoulder member having secured thereto a cylindrical pin of diameter approximately equal to the inside diameter of an envelope flap-fold, said pins projecting towards each other and remaining in alinement as the chains move, an envelope feed magazine including a powered feed belt having a substantially horizontal portion forming in part at least the floor of said magazine and a guide plate forming a side of said magazine, said substantially horizontal portion of the belt being adapted to support a stack of envelopes standing on edge with their flap-folds uppermost, their flaps folded down adjacent their respective bodies and their ends guided by said plate, and to propel them in the direction in which their flaps extend, said feed magazine being mounted to deliver envelopes successively to a position at the lower end of said straight line of chain ascent in which the concave surfaces of the fold at each end of the flap of the envelope are simultaneously presented in the path of travel of said pins and the ends of said envelopes are presented between and immediately adjacent to the paths of travel of said shoulder members, whereby envelopes are successively extracted from the magazine by said pins and are guided while in the magazine and after extraction therefrom by said guide plate and said shoulder members, and means to drive the powered feed belt in relation to the speed of the chains such that successive envelopes in the stack are delivered to successive pairs of pins as the chains move.

4. An envelope feeder comprising two endless chains working in unison along substantially parallel paths a predetermined distance apart, rotatable sprockets for said chains mounted to cause said chains during one portion of their paths of travel simultaneously to ascend in straight lines in a generally upward direction, a plurality of pairs of lugs secured to said chains at uniformly spaced intervals along the same, one lug in each pair being secured to one of said chains in opposed relation to the other lug of said pair, each lug having a projecting portion shaped to penetrate beneath the folded flap of an envelope and to engage the concave surface of the fold at each end of said flap, the projecting portions in each pair of lugs projecting towards each other and remaining in alinement as the

chains move, an envelope feed magazine including a powered feed belt having a substantially horizontal portion forming in part at least the floor of said magazine and a guide plate forming a side of said magazine, said substantially horizontal portion of the belt being adapted to support a stack of envelopes standing on edge with their flap-folds uppermost, their flaps folded down adjacent their respective bodies and their ends guided by said plate, and to propel them in the direction in which their flaps extend, said feed magazine being mounted to deliver envelopes successively to a position between the chains where the concave surfaces of the fold at each end of their flaps are simultaneously presented in the path of travel of said lug projections for upward extraction of an envelope from the magazine as a pair of lugs moves upwardly along the substantially straight line portion of the chain paths, and means to drive the powered feed belt in relation to the speed of the chains such that successive envelopes in the stack are delivered to successive pairs of lugs as the chains move.

5. An envelope feeder comprising two endless chains working in unison along substantially parallel paths a predetermined distance apart, lower and upper pairs of rotatable sprockets for said chains mounted to cause said chains while passing from the lower to the upper pair of sprockets simultaneously to ascend in straight lines in a generally upward direction and to turn towards a generally horizontal direction around said upper sprockets, a plurality of pairs of lugs secured to said chains at uniformly spaced intervals along the same, one lug in each pair being secured to one of said chains in opposed relation to the other lug of said pair, each lug having a projecting portion shaped to penetrate beneath the folded flap of an envelope and to engage the concave surface of the fold at each end of said flap, the said portions projecting towards each other and remaining in alinement as the chains move, an envelope feed magazine including a powered feed belt having a substantially horizontal portion forming in part at least the floor of said magazine and a guide plate forming a side of said magazine, said substantially horizontal portion of the belt being adapted to support a stack of envelopes standing on edge with their flap-folds uppermost, their flaps folded down adjacent their respective bodies and their ends guided by said plate, and to propel them in the direction in which their flaps extend, said feed magazine being mounted to deliver envelopes successively to a position between the chains where the concave surfaces of the fold at each end of their flaps are simultaneously presented in the path of travel of said lug projections for upward extraction of envelopes from the magazine as the lugs move upwardly along the said straight line portion of the chain paths, metal guide strips positioned between the chains and adjacent the upper sprockets to guide envelopes extracted from the magazine as they pass under control of the lugs around said upper sprockets, and means to drive the powered feed belt in relation to the speed of the chains such that successive envelopes in the stack are delivered to successive pairs of lugs as the chains move.

6. An envelope feeder comprising two endless chains, at least three pairs of rotatable sprockets, the sprockets in each pair being co-axially mounted and of equal diameter, over which said chains run, said pairs being mounted to cause said chains

during one portion of their paths of travel to ascend in a common plane in a generally upward direction from the first to the second pair of sprockets, and to turn around said second pair of sprockets for further movement in a common plane in a generally horizontal direction towards and over the third pair of said sprockets, a plurality of pairs of lugs secured to said chains at uniformly spaced intervals along the same, one lug in each pair being secured to one of said chains in opposed relation to the other lug of said pair, each lug comprising a cylindrical pin and at least one of said lugs including also a shoulder member, the pins being of diameter approximately equal to the inside diameter of an envelope flap-fold and projecting towards each other and remaining in alinement as the chains move, and the shoulder member having a guide face in a plane at right angles to the axis of the pins and disposed generally in the plane of operation of the chain to which it is secured, an envelope feed magazine including a powered feed belt having a substantially horizontal portion forming in part at least the floor of said magazine, said substantially horizontal portion of the belt being adapted to support a stack of envelopes standing on edge with their flap-folds uppermost, their flaps folded down adjacent their respective bodies and their ends guided by said plate, and to propel them in the direction in which their flaps extend, said feed magazine being mounted to deliver envelopes successively to a position at the lower end of said straight line of chain ascent in which the concave surfaces of the fold at each end of the flap of

the envelope are simultaneously presented in the path of travel of said pins and an end of said envelope is presented adjacent to the path of travel of the guide faces of said shoulder members, the sprockets of said third pair of sprockets being closer together than the sprockets of said first pair in order to cause said chains to converge in their travel whereby the guide faces of the shoulder members are brought into contact with the ends of envelopes being moved under control of said pins to index the said envelopes for subsequent processing, and means to drive the powered feed belt in relation to the speed of the chains such that successive envelopes in the stack are delivered to successive pairs of chains as the chains move.
